(21) Appl. No.: **29/169,393**

(57) CLAIM

(22) Filed: **Oct. 18, 2002**

The ornamental design for a mouse pad calculator with wrist rest and radio, as shown and described.

(51) LOC (7) Cl. **14-02**

DESCRIPTION

(52) U.S. Cl. **D14/458**

FIG. 1 is a top plan view of a mouse pad calculator with wrist rest and radio showing my new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a bottom plan view thereof; and,
FIG. 7 is a perspective view of FIG. 1 thereof.

(58) Field of Search D14/458-461; D10/2; D18/2, 6, 7, 11; 248/118.1; 345/156-167; 400/689-693; D19/65

The digital numerals in the display area and the numerals, letterings, and symbols in the key-pad area in FIG. 1 and FIG. 7 are for illustrative purposes only and form no part of the claimed design.
